Adrian D. Clem, Sioux City, Iowa

Application June 22, 1945, Serial No. 120,241

Term of patent 14 years

(Cl. D34—5)

To all whom it may concern:

Be it known that I, Adrian D. Clem, a citizen of the United States of America, residing at Sioux City, in the county of Woodbury and State of Iowa, have invented a new, original, and ornamental Design for a Game Board or the like, of which the following is a specification, reference being had to the accompanying drawings, forming a part thereof.

In the drawings:

Figure 2,

Figure 2.

I claim:

The ornamental design for a game board or the like, as shown.

ADRIAN D. CLEM
